UNITED STATES PATENT OFFICE.

MARK LAZARUS, OF PHILADELPHIA, PENNSYLVANIA, ASSIGNOR TO AUGUSTUS A. LAZARUS, ISAAC A. SCIWARZ, AND BENJAMIN LIPPER, OF SAME PLACE.

DESIGN FOR TRIMMING.

SPECIFICATION forming part of Design No. 21,649, dated June 21, 1892.

Application filed May 21, 1892. Serial No. 433,913. Term of patent 3½ years.

To all whom it may concern:

Be it known that I, MARK LAZARUS, a citizen of the United States, and a resident of Philadelphia, Pennsylvania, have invented a new and original Design for Dress-Trimming, of which the following is a specification.

My design is fully shown in the accompanying drawing, which represents a face view of a piece of the trimming.

The design comprises the central tape-like band or ribbon *a*, adjacent to each edge of which are narrow bands *b*, and projecting beyond these bands are arch-like loops *c*, alternating with longer loops *f*. Cords *i* ex-

tend in parallel wave-like courses across the central band *a* from one edge to the other and form short loops within the arched loops *d*.

I claim—

The design for dress-trimming, substantially as described, and as shown in the accompanying drawing.

In testimony whereof I have signed my name to this specification in the presence of two subscribing witnesses.

MARK LAZARUS.

Witnesses:

WILLIAM D. CONNER,
HARRY SMITH.
